UNITED STATES PATENT OFFICE

OLIVER J. HOWE, OF BROCKTON, MASSACHUSETTS, ASSIGNOR TO DANIEL C. REBHUN,
OF CINCINNATI, OHIO

LAST

Application filed September 5, 1929. Serial No. 390,557.

The present invention relates to lasts and more especially to an improved hinged last.

One of the objects of the invention is to provide a simple, efficient and economical connecting means for a hinged last which will maintain the toe and heel parts of the last in tight and proper position at all times and will not become worn or loose due to constant usage.

10 A further object of the invention consists in connecting the toe and heel parts of the last by a rigid member, so that the transverse anchor pins which pivotally secure the rigid member in position, will be maintained at their proper distance at all times, thus preventing any strain or yielding of the anchor pins when the parts of the last are moved relative to one another.

20 A further object comprehends the provision of guard members positioned between the rigid member and the adjacent side walls of the last, to prevent the parts from becoming loose or worn due to the frictional engagement of the rigid member with the side walls 25 of the last, said guard members being constructed and arranged to permit the rigid member to be moved relative thereto when the forepart and heel part of the last are moved to either their expanded or contracted 30 positions.

Other objects and advantages of the invention will become apparent from the following description when taken in conjunction with the accompanying claims and drawings.

35 In the drawings which disclose several preferred embodiments of the invention,

Figure 1 is a side elevation of the last in expanded position with parts in section.

40 Figure 2 is a view similar to Figure 1, showing the last in collapsed position.

Figure 3 is a sectional view taken substantially along the line 3-3 of Figure 1.

45 Figure 4 is an exploded view of the connecting means.

Figure 5 is a side elevation of a modified form of the invention, with parts in section, and showing the last in its expanded position.

50 Figure 6 is a view substantially similar to

Figure 5, with the last in its collapsed position.

Figure 7 is an exploded view of the connecting means shown in Figures 5 and 6.

Referring to the drawings in which like numerals indicate like parts, in the several views, 10 generally denotes a hinged last for boots or shoes, which is composed of the toe part 11 and the heel part 12, the toe part 11 preferably being provided with a transversely disposed concave recess 13 arranged to receive a complementary formed knuckle 14, on the heel part 12, so as to provide a socket joint for permitting the parts to be moved relative to each other. The inner face 15 of the heel part is cut away to allow the last to be moved from its extended position to its collapsed position while the downward movement of the last is limited by the abutting faces 16 formed on the lower portions of the toe and heel parts.

The forepart 11 and heel part 12 are formed with the longitudinally extending medially disposed cut-away portions 17 and 18, which, when the parts are in their expanded position, are in alignment with each other. Mounted within the cut-away portions 17 and 18 is a rigid metallic member preferably in the form of an elongated flat plate 19, which may be of any suitable shape or configuration and has adjacent its ends the openings 20 and 21 (Fig. 4). The rigid member 19 is pivotally mounted within the cut-away portions 17 and 18 by the anchor pins or bolts 22 and 23 which extend transversely through the toe part 11, heel part 12 and the openings 20 and 21. Associated with the plate 19, are the metallic guard members 24 and 25, which are arranged between the plate 19 and the adjacent walls of the cut-away portions 17 and 18, so as to prevent the plate 19 from being brought into frictional engagement with the side walls of said cut-away portions when the toe and heel parts of the last are moved from one position to another. Each of the guard members or plates 24 and 25 is provided adjacent its ends with openings 26 of slightly larger diameter than the openings 20 and 21 and in alignment

therewith, so as to receive the anchor pins 22 and 23, when the parts are set up.

By reason of the free movement imparted to the plate or center piece 19, relative to the guards 24 and 25, means are provided for preventing the plate 19 from being brought into wearing contact with the adjacent walls of the cut-out portions 17 and 18, thus preserving the snug and tight fit initially put into the last when the parts are assembled.

Due to the rigidity of the plate 19, the anchor pins 22 and 23 are prevented from yielding or stretching when the toe and heel parts are snapped into either their expanded or contracted positions and consequently the anchor pins will be maintained at all times in their proper and correct position while the efficiency of the last will be unaffected by constant usage.

In the modified form of the invention illustrated in Figures 5, 6 and 7, the toe part 27 is pivotally connected to the heel part 28 of the last by a substantially rigid plate 29 which is provided adjacent its ends with the openings 30 for receiving the anchor pins 31 which extend transversely through these parts and the cut-out portions 32.

In order to prevent the plate 29 from being brought into rubbing engagement with the adjacent walls of the cutout portions 32, a guard plate is provided, which plate is preferably composed of the split sections 33 and 34 that are substantially U-shaped in cross-section, so as to constitute the parallel sides 35 and 36 between which the plate 29 is positioned. The guard members 33 and 34 are each formed adjacent their outer ends with the openings 37 which are of substantially the same diameter as the openings 30 in the plate 29 and are supported by the anchor pins 31 when the parts are set up.

In order that the plate 29 may be moved relative to the guard members without these members riding therewith when the last is carried to either its expanded or contracted positions, the inner opposed faces 38 of the guard members are preferably inclined and spaced from each other. The guard members 33 and 34, in addition to preventing the plate 29 from being brought into rubbing engagement with the adjacent walls of the last, also tend to take up and receive the strain from the pins 31 and thus insure the parts from becoming worn or loose.

It is to be understood that the several forms of the invention herewith shown and described are merely illustrative of preferred embodiments and that such changes may be made therein as fall within the purview of one skilled in the art without departing from the spirit of the invention and the scope of the appended claims.

What I claim is:

1. A hinged last comprising a toe part and a heel part, said parts having longitudinally

disposed cut-out portions, a plate within said cut-out portions, anchor pins extending transversely through said toe and heel parts and pivotally supporting the ends of said plate, guard members within said cut-out portions and pivotally connected to said anchor pins, said guard members being positioned between said plate and the adjacent walls of said cut-out portions, and means for permitting the movement of the plate relative to said guard members.

2. A hinged last of the class described comprising toe and heel parts, one of said parts having a transversely disposed curved recess and the other part a knuckle arranged to fit into said recess, said parts having longitudinally aligned medial cut-out portions, a plate within said cut-out portions and having an opening adjacent each end thereof, a guard member on each side of said plate and having openings adjacent the ends thereof in alignment with the openings in said plate, and anchor pins extending transversely through said toe and heel parts and said opening.

3. A hinged last of the class described comprising toe and heel parts, one of said parts having a transversely disposed curved recess and the other part a knuckle arranged to fit into said recess, said parts having longitudinally aligned medial cut-out portions, a rigid member within said cut-out portions and having an opening adjacent each end thereof, a guard member on each side of said rigid member and having openings adjacent the ends thereof of larger diameter than the openings in said rigid member and in alignment therewith, and anchor pins extending transversely through said toe and heel parts and said openings, said rigid member acting to maintain said pins in their proper position at all times and said guard members tending to prevent the parts from becoming worn or loose.

4. A hinged last of the class described comprising toe and heel parts, one of said parts having a transversely disposed curved recess and the other part a knuckle arranged to fit into said recess, said parts having longitudinally aligned medial cut-out portions, a plate within said cut-out portions and having an opening adjacent each end thereof, guard members on each side of said plate and having openings adjacent the ends thereof in alignment with the openings in said plate, and anchor pins extending transversely through said toe and heel parts and said openings, said guard members having opposed spaced sides for permitting the plate to move relatively thereto.

5. A hinged last of the class described comprising toe and heel parts, one of said parts having a transversely disposed curved recess and the other part a knuckle arranged to fit into said recess, said parts having longitudinally aligned medial cut-out portions, a plate

- within said cut-out portions and having an opening adjacent each end thereof, guard members on each side of said plate and having openings adjacent the ends thereof in alignment with the openings in said plate, and anchor pins extending transversely through said toe and heel parts and said openings, said guard members having opposed inclined spaced end portions for permitting the plate to be moved relative thereto.
6. A hinged last of the class described comprising toe and heel parts, one of said parts having a transversely disposed curved recess and the other part a knuckle arranged to fit into said recess, said parts having longitudinally aligned medial cut-out portions, a plate within said cut-out portions and having an opening adjacent each end thereof, a substantially U-shaped guard member extending parallel with said plate and having openings in alignment with the openings in said plate, said guard member being medially split to provide inclined opposed spaced end portions for permitting the plate to be moved relative thereto, and pins extending transversely through said last and said openings for movably maintaining the plate and guard member in position.
10. A hinged last of the class described comprising toe and heel parts, one of said parts having a transversely disposed curved recess and the other part a knuckle arranged to fit into said recess, said parts having longitudinally aligned medial cut-out portions, a plate within said cut-out portions and having an opening adjacent each end thereof, a substantially U-shaped guard member extending parallel with said plate and having openings in alignment with the openings in said plate, said guard member being medially split to provide inclined opposed spaced end portions for permitting the plate to be moved relative thereto, and pins extending transversely through said last and said openings for movably maintaining the plate and guard member in position.
15. A hinged last of the class described comprising toe and heel parts, one of said parts having a transversely disposed curved recess and the other part a knuckle arranged to fit into said recess, said parts having longitudinally aligned medial cut-out portions, a plate within said cut-out portions and having an opening adjacent each end thereof, a substantially U-shaped guard member extending parallel with said plate and having openings in alignment with the openings in said plate, said guard member being medially split to provide inclined opposed spaced end portions for permitting the plate to be moved relative thereto, and pins extending transversely through said last and said openings for movably maintaining the plate and guard member in position.
20. A hinged last of the class described comprising toe and heel parts, one of said parts having a transversely disposed curved recess and the other part a knuckle arranged to fit into said recess, said parts having longitudinally aligned medial cut-out portions, a plate within said cut-out portions and having an opening adjacent each end thereof, a substantially U-shaped guard member extending parallel with said plate and having openings in alignment with the openings in said plate, said guard member being medially split to provide inclined opposed spaced end portions for permitting the plate to be moved relative thereto, and pins extending transversely through said last and said openings for movably maintaining the plate and guard member in position.
25. A hinged last of the class described comprising toe and heel parts, one of said parts having a transversely disposed curved recess and the other part a knuckle arranged to fit into said recess, said parts having longitudinally aligned medial cut-out portions, a plate within said cut-out portions and having an opening adjacent each end thereof, a substantially U-shaped guard member extending parallel with said plate and having openings in alignment with the openings in said plate, said guard member being medially split to provide inclined opposed spaced end portions for permitting the plate to be moved relative thereto, and pins extending transversely through said last and said openings for movably maintaining the plate and guard member in position.

In testimony whereof I have hereunto set
30 my hand.

OLIVER J. HOWE.
